R. SALAMON

WINDOW LOCK AND ALARM

Filed Nov. 20, 1920

BY

ATTORNEY

19.3. INVENTOR
Hudor Salamony
ATTORNEY Richard Oliver

UNITED STATES PATENT OFFICE.

RUDOLF SALAMON, OF NEW YORK, N. Y.

WINDOW LOCK AND ALARM.

Application filed November 20, 1920. Serial No. 425,381.

To all whom it may concern:

Be it known that I, RUDOLF SALAMON, a citizen of Yugoslavia, residing at New York city, in the county of New York and State 5 of New York, have invented certain new and useful Improvements in Window Locks and Alarms, of which the following is a specification.

This invention has relation to window 10 locks and has for an object to provide a combined window lock and alarm device, intended for application to the sashes of a window and including means for locking the sashes together in any relatively adjusted 15 position, and for locking one of the sashes to the window frame, whereby they may be immovably held, thus permitting the sashes to be locked in an open position to secure ventilation.

20 Another object of the invention is to provide a combined window lock and alarm device having the characteristics above set forth and including in addition thereto an alarm mechanism operatively associated with 25 the locking devices so that in the event that one or the other of the sashes are moved in an attempt to raise or lower the same the alarm mechanism will be actuated to sound a signal.

30 In addition to the foregoing this invention comprehends improvements in the details of construction and arrangement of parts to be hereinafter described and particularly set forth in the appended claim.

35 In the accompanying drawings in which similar and corresponding parts are designated by the same characters of reference throughout the several views in which they appear.

40 Figure 1 is a view in vertical section through a combined window lock and alarm device constructed in accordance with my invention and illustrating the meeting edges of the sashes in edge view.

45 Fig. 2 is a view thereof in vertical section.

Figure 3 is a view in top plan of the device and

Figure 4 is a detail view in section.

50 With reference to the drawings, 10 indicates the lower sash and 11 the upper sash. Applied to the front face of the upper sash is a vertical rail 12 having a plurality of vertically spaced square openings 13 therein.

55 The window frame is indicated at 14 and secured to the side face thereof is a vertical

rail 15 likewise having openings 16 formed therein in spaced relation. Mounted upon the top edge of the lower sash 10 is a plate 17 having a sleeve 18 formed therein extending transversely of the sash and designed to receive a threaded rod 19. To the inner end of the rod there is secured a square block 20 which is provided with a reduced extension 21 entering an opening in the rod 19 and held therein against dislodgement but in a manner to permit rotation of the rod 19 and block 20 relatively. It will be obvious that by rotating the rod 19 the block 20 may be inserted in any one of the square openings 13 of the rail 12 and in this manner the sashes are locked together against relative movement.

The device further consists of a rectangular casing 22 which is secured to the front face of the lower sash and in which there is mounted a horizontal locking bar 23 designed for sliding movement and adapted to enter one of the openings 16 of the rail 15. The block is shifted by means of the pinion 24 which is mounted upon a rod 25 and which engages teeth formed in the lower edge of the bar 23. It will be noted that the outer end of the bar is adapted for slight vertical oscillation for a purpose to be presently noted. I also provide a chain of gears consisting of the winding shaft 26 upon which is loosely mounted the gear wheel 27. A coil spring is provided as indicated at 28 having one end secured to the winding shaft 26 and the other end secured to any stationary support. The shaft 26 rigidly carries a ratchet wheel 29 and a pawl 30 is mounted on the spur wheel 27 and adapted to engage the ratchet wheel 29 so that when the winding shaft 26 is rotated the spring 28 may be wound up or placed under tension and the power expended by the unwinding efforts of the spring and imparted to the gear wheel 27 through the medium of the pawl 30 and ratchet wheel 29. The wheel 27 meshes with a pinion 31 which also carries a relatively large spur wheel 32, the latter in turn meshing with a pinion 33 which is formed with an escapement wheel 34 of the conventional type adapted for cooperative relation with an escapement lever 35. To one end of said lever 35 there is connected a link 36 which in turn is pivotally connected to an arm 37 pivotally mounted within the casing and carrying at its outer end a hammer 38 designed to strike a gong 39. A lever 40 is

provided and is pivotally mounted within the casing having a lip 41 at its upper end designed to normally engage between adjacent teeth of the escapement wheel 34. One edge of the lever 40 is cut away in a semi-circular manner as indicated at 41 and a pin 43 extending laterally from the locking bar 23 is normally seated and engages the cut away edge 42 of said lever. The lower end 10 of the lever may extend beyond the casing as shown.

It will be seen that when the locking bar 23 is engaged in one of the openings of the rail 15 the sashes are held against movement relative to the frame. Thus, by adjusting the sashes relatively to secure ventilation at the top and bottom they may be held in this position by means of the locking mechanism shown in detail in Figure 4, 20 and to prevent movement of the locked sashes relative to the frame the locking bar 23 is moved to locked position in the manner described. It will be noted that the lip 41 is in engagement with the escapement wheel and normally holds the alarm mechanism against operation. However, should an attempt be made to raise or lower the sashes the result will be a vertical oscillatory movement of the locking bar 23, 30 which will cause the pin 43 to ride against the cut away edge 42 of the lever 40; thus moving said lever outward at its upper end to a position where the escapement wheel 34 becomes disengaged. Then, the force of the spring 28 is extended through the chain of gearings to rotate said escapement wheel and operate the escapement mechanism causing the hammer 38 to oscillate and strike the gong 39 thus sounding the 40 signal. Operation of the device may be discontinued by slightly moving the lower end of the lever 40 to reengage the upper end with the escapement wheel.

Thus, it will be seen that I have provided 45 a novel device which is characterized by

the provision of means whereby ventilation may be readily secured in a room by the proper relative adjustment of the sashes without any possibility of the same being opened to any greater distance sufficient to 50 permit the entrance of anyone through the window opening. Furthermore, it will be found that by reason of this device if any such attempt be made the occupants of the building may be readily warned to prevent 55 further damage in the mechanism in the event that an entrance be forced. Other uses and advantages will readily occur to those familiar with the art to which this invention appertains. 60

While I have illustrated and described my invention with some degree of particularity, I realize that in practice various alterations therein may be made. I therefore reserve the right and privilege of 65 changing the form of the details of construction without departing from the spirit of the invention or the scope of the appended claim.

Having thus described my invention what 70 I claim as new and desire to secure by United States Letters Patent is:—

In combination, a casing, a horizontal rack bar slidable therein, a rail having perforations to receive the end of the locking 75 bar, a pin extending laterally from the locking bar, a train of gearing including an escapement wheel and escapement mechanism, a lever having a cut away portion against which the pin bears and having its end normally in engagement with the escapement wheel to prevent operation of the gearing, and an alarm mechanism operable by the escapement mechanism.

In testimony whereof I affix my signature in presence of a witness.

RUDOLF SALAMON. [L.S.]

Witness:

W.M. ZEAMAN.
